EDIBLE SERVING SPOON

James Gordon, 3625 N. Halsted St., Chicago, Ill.

Filed Dec. 21, 1961, Ser. No. 68,018

Term of patent 14 years

(Cl. D8—1)

FIG. 1

FIG. 3

FIG. 1 is a front perspective view of an edible serving spoon, showing my new design;

FIG. 2 is a rear elevational view thereof; and

FIG. 3 is a side elevational view thereof.

I claim:

The ornamental design for an edible serving spoon, as shown.
